UNITED STATES PATENT OFFICE.

WILLIAM N. WHITELEY, WILLIAM BAYLEY, AND OSCAR E. PERRIGO, OF SPRINGFIELD, OHIO, ASSIGNORS TO SAID WILLIAM N. WHITELEY.

GRAIN-BINDING HARVESTER.

SPECIFICATION forming part of Letters Patent No. 398,921, dated March 5, 1889.

Application filed April 1, 1886. Serial No. 197,436. (No model.)

To all whom it may concern:

Be it known that we, WILLIAM N. WHITELEY, WILLIAM BAYLEY, and OSCAR E. PERRIGO, citizens of the United States, residing at Springfield, in the county of Clark and State of Ohio, have invented certain new and useful Improvements in Grain-Binders; and we do hereby declare that the following is such a full, clear, and exact description of the same as to enable any person skilled in the art to which our invention pertains to construct and operate the same, reference being had to the accompanying drawings, forming a part of this specification.

Our invention relates, in general terms, to that class of automatic grain-binding harvesters wherein the grain is bound between the grain-platform and the main driving-wheel; and it consists in the construction and arrangement of the various parts composing the mechanism for elevating, binding, and discharging the cut grain, and in the devices provided for driving the same, as hereinafter more particularly described and pointed out.

In the drawings, Figure 1 is a perspective view of our machine as a whole. Fig. 2 is a front elevation, Fig. 3 is a rear elevation, and Fig. 4 is a transverse section, of the machine, the grain-platform, reel, &c., being omitted. Fig. 5 is an enlarged view of the "trip" or "set-off" device for throwing the binding mechanism into and out of gear. Fig. 6 is a sectional plan of the packer-shaft and its appendages. Fig. 7 is a perspective view of the starter-pawl, and Fig. 8 is a longitudinal section of a modification of the elevator-belts and parts of the binding device.

Several parts not necessary to the proper understanding of the machine are omitted in one or more views to avoid needless complications.

Similar letters refer to like parts in the several views.

A A is the main frame of the machine, to which the main wheel B is journaled in the usual manner. The main wheel B has fixed to it the bevel-wheel B², which engages the bevel-pinion B³ on the counter-shaft b, upon the outer or rear end of which is fixed the spur-gear B⁴, engaging the spur-pinion B⁵ on the crank-shaft b², upon the opposite or front

end of which is fixed the fly-wheel B⁶, from the fixed wrist-pin b³ of which extends the pitman b⁴ to the cutter-bar b⁵, as shown, and as usually arranged.

Formed upon the spur gear-wheel B⁴, cast in one piece with it or secured to it or to the counter-shaft b, is the sprocket-wheel C, from which power is transmitted by the chain c c to the sprocket-wheel C² for driving the elevating, binding, and discharging mechanism, to the sprocket-wheel C³ for driving the platform or conveyer-belt, and to the sprocket-wheel C⁴ for driving the reel. The reel D D is operated through the medium of the shaft c², bevel-gears c³ and c⁴, sprocket-wheels C⁵, C⁶, C⁷, and C⁸, and chains c⁶ and c⁷, and is provided with the adjusting-lever c⁸ and its appendages, all arranged in the usual manner.

A² A³ A⁴ A⁵ A⁶ A⁷ A⁸ are the parts composing the upper frame, which is attached to and forms a part of the main frame A A, and encloses and supports the elevating, binding, and discharging mechanism, as well as furnishes the support for the reel D, while upon the seat-board A⁸ is fixed the driver's seat Z, all in the usual manner.

The platform E and its appendages are constructed as usual, fixed to the main frame, and supported at the grain end by the usual grain-wheel, E², attached as may be most convenient.

The elevating, binding, and discharging mechanism is supported by a frame-work composed of the side boards, F F, cross-bar F² F³, deck-supports F⁴, brace F⁵, middle rails, F⁶, breast-plate F⁷, and frame-plates F⁸. This frame is supported within the upper portion of the main frame as follows: Fixed to the sill A of the main frame is the gas pipe or tube f, upon which rest the friction-wheels f² f³, pivoted to brackets fixed to the side boards, F F. Fixed to the frame-plates F⁸ F⁹ is the gas-pipe f³, its ends projecting forward and back, and sliding loosely through the boxes f⁴ f⁵, fixed to the posts A² and A³. Fixed to the outer sill of the main frame is the upwardly-projecting bracket a, having pivoted in it the friction-wheel a², upon which rests the girt a³, fixed to the under side of the discharge-deck O, which is kept from rising out of place by a portion of the bracket a being looped over

the girt a^3 . The adjustment of the binding mechanism in its relation to the cutting mechanism, to suit the varying lengths of grain, is thus secured, and is controlled by the crank-lever d , shaft d^2 , and pinion d^3 , engaging the rack d^4 , fixed to the gas-pipe f^3 in the usual manner.

The elevator-belts V V^2 are constructed as usual, except that the upper one extends only about half the usual distance up the incline, and that the belts are divided—*i. e.*, each composed of two belts running parallel to each other and far enough apart to admit of the free operation of the binding mechanism between them, as shown in Fig. 1. The belts are driven by the rollers V^3 V^4 and pass over the upper rollers, V^5 V^6 .

The binding mechanism is constructed upon the well-known plan described in Letters Patent No. 212,420, granted to John F. Appleby February 18, 1879, modified to suit the requirements of this form of constructing and arranging the machine—to wit, binding the grain between the platform and the main driving-wheel.

The binder-frame Q is fixed to the side board, F , and carries the knotter-shaft q , binder sprocket-wheel K , tyer-wheel W^2 , and knotter W .

The packer-shaft G (shown in detail in Fig. 6) is driven by the chain c , passing over the sprocket-wheel C^2 , through which it passes and is permitted to slide freely, but is kept from turning thereon by the spline g , traveling in the slot g^2 of the packer-shaft, as usual. The shaft is supported in the binding mechanism by passing through the frame-plates F^8 F^8 , between which the shaft has formed upon it two packer-cranks, g^3 g^3 , to which are pivoted the lower ends of the packers G^2 G^2 . The packers are suspended and kept in their proper paths by the links g^4 g^4 , pivoted at one end to the packers near their center and at the other to the frame-plates F^8 . The packer-shaft G , rotating in the direction of the arrow, moves the packers alternately upward between the elevator-belts, forcing the grain against the compressor H , and returning beneath the lower elevator-belt, the points of the packers following, in direction of the arrow, the dotted lines, as shown in Fig. 4. By this method of constructing and arranging the packers two important results are accomplished over the usual form, viz: First, the packer has a much longer and more direct throw against the grain, its ascent being a long, gradual, upward sweep, while it withdraws itself freely from the grain, with no shearing motion, and travels quickly back to its first point in the most practically direct line; second, by so constructing and hanging the packers they occupy much less space longitudinally, and the main driving-wheel may therefore be set much nearer the grain-platform and a more proper balance of the machine secured.

The needle-arm J is fixed upon the shaft j , which passes through to the front of the machine, where it has the arm j^2 fixed to it, by which it is operated by the pitman j^3 , connecting at its upper end with the crank-wrist of the binder sprocket-wheel K in the usual manner. The needle-arm J is composed of three parts pivoted to each other—*i. e.*, the needle-arm J proper, the curved back piece, J^3 , and the link J^4 . The back piece, J^3 , has one end pivoted to the needle-arm proper and the other to the link J^4 , whose opposite end is pivoted to some fixed point of the binder-frame. By this arrangement, when the needle-arm J is thrown up to encircle the gavel, the link J^4 , swinging upon its fixed pivot, carries the end of the back piece, J^3 , which is pivoted to it, into such a position that it shall form an arc of a circle in prolongation with the arc formed by the back of the needle-arm, from its point to the pivot of the back piece, J^3 , by which construction the needle-arm is practically as useful as the usual form, while it occupies only about two-thirds of the space longitudinally that is usually required, and the main driving-wheel can be set that distance closer to the grain-platform. The operations of the needle-arm in its functions of encircling the gavel, carrying the binding-cord, presenting it to the knotting device, &c., are all performed in the usual manner.

The compressor H is pivoted at its lower end to a projection on the needle-arm J , while its upper end is supported by the link H^2 , connecting it with the arm H^3 , fixed upon the compressor-shaft h , which passes through to the front of the machine, where it has fixed to it the arm H^4 , operated by the spring connecting-rod h^2 and cam-lever h^3 , whose friction-roller works in a cam-track formed upon the binder sprocket-wheel K in the usual manner, with the exception that as the arm j^2 must be forced downward in the act of binding, instead of being drawn upward, (owing to the changed location of the binding device,) the cam-track is formed accordingly.

Upon the front end of the packer-shaft G is fixed the sprocket-wheel G^3 , from which the chain g^5 passes around the sprocket-wheel V^7 and over the sprocket-wheel V^8 , by which means the elevator-belts V and V^2 are operated continuously. Still nearer the front end of the packer-shaft G is the sprocket-wheel L , turning loosely upon the shaft and having pivoted to its face the pawl or dog L^2 . Outside of the sprocket-wheel L , and fixed to the packer-shaft G , is the continuously-revolving head L^3 , having the friction-rollers l^1 pivoted at each end thereof. Upon the dog L^2 is formed a projection, l^2 , which, when the dog is in the position shown by dotted lines in Fig. 5, is engaged by one of the friction-rollers l^1 , whereby the sprocket-wheel L is rotated. The dog L^2 is held in the position shown in the drawings by a projection, l^4 , coming in contact with the end of the trip-

ping-lever M, which is pivoted to the bracket M², fixed to the side board, F. When the binding mechanism is at rest, the tripping-lever M is held down by the spiral spring m, which 5 is confined upon the bent rod m² by a thumb-nut, m³, the upper end of the rod m² being pivoted to the tripping-lever M, which now rests on the projecting curved point of the bracket M². The pawl or dog L² is held in 10 contact with the tripping-lever M by means of the spring l², fixed to the sprocket-wheel L. Upon the crank-arm j² (by which the needle-arm is actuated) is a projection nearly at right angles, to which is pivoted the connecting-rod M³, whose lower end is pivoted to the 15 starting-lever M. Formed upon the trip-rod M³, near its upper end, is a curved projection, m⁴.

N is the trip-arm, fixed to the trip-shaft n 20 near the center of the binder and immediately under the knotter W. The trip-shaft n runs through to the front of the machine, where it has fixed to it the curved arm N², in the end of which is a set-screw, n², whose point rests 25 under the curved projection m⁴ on the trip-rod M³.

The mechanism for starting the binder just described is substantially that usually employed; but the arrangement of the several 30 parts is more particularly referred to, as their disposition differs from that usually resorted to, and their operation is as follows, viz: The grain is packed upon the trip-lever N and against the compressor H by the packers G² 35 G³ until its weight forces down the trip-lever N to the position shown by dotted lines, Fig. 5, and raises the curved arm N², whose set-screw n² elevates the trip-rod M³ and starting-lever M far enough to release the dog L², which 40 is immediately forced to the position shown by dotted lines by the spring l², thus throwing the projection l² far enough outward to catch one of the friction-rollers l¹ on its way around, and thus set in motion the sprocket-wheel L, 45 from which the chain k runs over the binder sprocket-wheel K and ejector sprocket-wheel P, each of which makes one revolution to each bundle bound. Upon the binding mechanism being started, as just described, the arm j² swings over to the position shown by dotted 50 lines, Fig. 5, the needle-arm carries the cord to the knotter, and the bundle is bound in the usual manner. While the knot is being formed in the binding-cord the trip-lever N 55 is liable to be released from pressure and rise up by the weight of the trip-rod M³ and force of the spring m, which would bring down the starting-lever and stop the binding mechanism before it had performed its functions. To 60 avoid this the trip-rod M³ is pivoted at its upper end to the projection on the arm j², and when this arm is swung over to the position shown by dotted lines the connecting-rod M³ raises the starting-lever to the position shown 65 by dotted lines and holds it in that position until the needle-arm has performed its work

and falls back, when the trip-lever M is allowed to drop down to its original position, the end catching the upwardly-projecting portion of the dog L², throwing it into the position shown, and releasing the projection l² 70 from contact with the friction-roller l¹, which now revolves around outside of it while the binding mechanism stops. The packer-shaft continues to revolve and the packers to pack 75 the grain upon the trip-lever and against the compressor for the next bundle. The size of the bundles is regulated by the set-screw n², as usual.

Journalized in the supports F⁴ is the ejector-shaft p, having the ejector sprocket-wheel P fixed to its front end. The ejector-shaft p runs through to near the center of the binder, where it has fixed to it the ejector-crank p². Pivoted on one of the supports F⁴ is the friction-roller r, which is fitted to a curved slot 80 in the ejector R, whose lower end is pivoted to the ejector-crank p². The ejector sprocket-wheel P, being the same diameter as the binder sprocket-wheel K and driven by the same 85 chain, necessarily makes one revolution to each bundle bound. In the drawings the ejector is shown in its position when at rest—i. e., while the packers are at work accumulating a gavel to be bound. When a gavel has been formed 90 and the trip-lever has started the binding mechanism, the ejector-crank p² rotates in direction of the arrow and causes the point of the ejector to slowly travel along the dotted line from S to S² during the interval of the 95 movement of the needle-arm while encircling the gavel and while the knotter is forming the knot, at which movement the point x of the cam-track on the binder sprocket-wheel K has arrived at the friction-roller x² of the 100 cam-lever l², the cam raises the spring-rod h² and arm H¹, the compressor-shaft h rocks, carrying with it the arm H³, and by means of the link H² throws down the compressor H and releases the bound bundle. At the same time 105 the ejector commences its upward movement, and as the leverage from the pin of the crank p² and friction-roller r is very much reduced the motion of the ejector is correspondingly accelerated and travels from S² to S³ quickly, 110 carrying with it the bound bundle, which is forcibly snatched away from its position, separated from the unbound grain, and thrown out upon the ground, the deflector T² preventing the bundle from rising off the point of the 115 ejector. At this moment, the distance from the pin of the crank p² and friction-roller r becoming much increased, the ejector returns 120 without shock to its original position, with the point resting at S. 125

Instead of discharging the bundles upon the ground, as just described, they may be received in a bundle-carrier, as shown in Fig. 1. This device consists of a rock-shaft, t, pivoted in the supports F⁴, and having the arm t² fixed to one end thereof, while it is provided 130 with curved fingers T T, fixed at suitable in-

tervals for receiving and retaining several bundles. It is held in the position shown by the rod t^3 , pivoted to the arm t^2 , and terminating in a handle in reach of the driver. This 5 rod t^3 has formed in it two loops, u , (only one of which is shown,) which are engaged by a pin in the post A^2 . When a sufficient number of bundles have been collected in the bundle-carrier, the rod t^3 is released from the pin 10 in the post A^2 and the load dumped by the turning of the shaft t and consequent dropping of the fingers T T .

In practice it has been found that sometimes the grain may be very sparse over the 15 field and may be turned endwise, in which event it is scattered loosely over the conveying and elevating mechanism, and therefore to move the grain successfully there must be a moving surface upon which the grain is carried forward and upward in order to facilitate its elevation and accumulation for binding. Therefore we employ a conveying-belt, and also elevating-belts—in this case two belts—one on each side of the cord-carrying 20 or needle arm, for the grain to rest upon, while above the grain two similar belts are arranged to still further insure the proper elevation of the grain and its delivery to the packers. By this means we are enabled to convey the grain 25 perfectly, in whatever position it may be presented, to the elevator-belts and to securely deliver it to the binding mechanism, where it is compacted preparatory to being encircled by the band, the band knotted, the cord severed, and the bundle discharged by the mechanism herein described.

The elevator-belts V V^2 may be constructed as herein described, the lower belt, V^2 , taking the place of the usual stationary binding-deck, 40 or it may only reach to the needle-arm shaft J ; or the parts may be arranged as shown in Fig. 8. In this case a shaft, h^7 , is pivoted in the side boards, F F , and fixed to said shaft are fingers H^7 . Upon the front end of the 45 shaft h^7 may be an arm, to which may be pivoted a rod connecting it with the binding mechanism in such a manner that as soon as the binding mechanism is set off or started the shaft h^7 may rotate slightly, raising the fingers H^7 to the position shown by dotted lines, thus raising the accumulated 50 bundle clear from the elevating-belt V^2 , in order that the movement of the same may not disturb the free and effectual operation 55 of the binding mechanism. After the bundle is bound the fingers H^2 may again drop out of the way until another sheaf is accumulated.

We are aware that it is old to bind grain 60 over an intermittently-moving carrier, which carrier is, however, during the binding operation at rest. We are also aware that it is old to employ a feed mechanism which gives to the cut grain a step-by-step movement while 65 a sewing device unites it into a sort of gavel. Such earlier devices we disclaim, but believe

ourselves to be the first to dispense with a binding-deck which is stationary during the operation of the binding mechanism, and to bind directly upon the moving elevating-belts. 70

Having thus fully described our invention, its construction and operation, and without wishing to be understood as restricting our claims to invention to the precise forms, proportions, or arrangement of the parts, or to the particular device herein described, or to any devices not essential to the principle of construction and mode of operation of the improvements made by us and herein described, what we claim as new, and desire to 80 secure by Letters Patent, is—

1. In a self-binding harvester, the combination of a continuously-moving grain-carrier, a bundle-forming mechanism, a needle-arm operated from beneath, and a knotter mechanism situated over said grain-carrier and binding the grain while resting thereon. 85

2. In a grain-binding harvester wherein the binding mechanism is situated between the grain-platform and the drive-wheel, the combination of the inclined continuously-moving elevating-belt, which carries the grain over the drive-wheel, and a knotter mechanism situated over said belt, which binds the grain while resting on said moving belt. 90

3. In a grain-binding harvester, the combination of a continuously-moving elevating-belt divided substantially centrally and a binding mechanism situated over said belt and adapted to bind the grain into bundles 100 while resting on said belt, parts of said binding mechanism operating through the space between the parts of said divided belt. 95

4. In a grain-binding harvester, the combination of a continuously-moving lower elevating-belt divided substantially centrally, an upper elevating-belt moving in proximity to said lower belt, and also divided substantially centrally, and a binding mechanism which binds the grain into bundles while resting on said lower belt, parts of said binding mechanism operating in the space between the parts of said divided belts. 105

5. In a grain-binding harvester, the combination of a divided lower elevating-belt, a 115 binding mechanism situated between the edges of the adjacent parts of the belt, and having parts thereof operating in the space between the parts of said divided belt, and an upper elevator-belt traveling in proximity 120 to the lower belt and terminating near the knotting mechanism of the binder.

6. In a grain-binding harvester, the combination of a divided elevator-belt, rollers at the opposite ends of such belt, over which the 125 belt travels, the axes of rollers of the parts of the divided belt being in the same line, and a binding mechanism situated between the adjacent edges of the parts of said belt, and having parts thereof operating in the space 130 between the parts of the belt, substantially as set forth.

7. In a self-binding harvester, the combination of the needle-operating mechanism, a trip-arm, N, adapted to be depressed by the gavel, the dog L², a clutch-tripping lever, M, held normally in contact with said dog L², and a connecting-rod between the trip-arm and said clutch-tripping lever, said connecting-rod being also directly connected with and operated by the needle-operating mechanism,

whereby when the needle is in operation the 10
tripping-lever is free from dog L², regardless
of the position of the trip-arm, as set forth.
